UNITED STATES PATENT OFFICE.

CHARLES F. SMITH, OF FOREST PARK, ILLINOIS.

MUSICAL INSTRUMENT.

Application filed February 2, 1924. Serial No. 690,117.

My new instrument is of the type represented by the clarinet, saxophone, etc., and among the objects of my invention are to produce a new instrument of this type; to produce a new instrument of this type operated by means of a keyboard; to connect this keyboard to the instrument in such a way that the right hand of the performer can operate said keyboard substantially in the same manner as the right hand plays single tones upon the modern piano and with the same knowledge acquired through practice upon the piano; to have tones at the lower end of the upper register duplicate those at the upper end of the lower register, thereby reducing greatly changing registers; to reduce to but three items the operation of said instrument, first, blowing of the reed, second, pressing of but one key with one finger, third, operation of the register key; to accomplish the result just stated and still have an instrument where the speed and facility of action are the greatest and where the impedimental conditions have been removed; to have a keyboard of such a design that both registers can be handled with the variations in said keyboard in such places as to cause the least annoyance; to produce a keyboard instrument of the kind referred to such that there will be a minimum number of variations from standard keyboard arrangement; and such further objects, advantages and capabilities as will hereafter more fully appear and as are inherent in the construction disclosed.

My invention further resides in the combination, construction and arrangement of parts illustrated in the accompanying drawings in which Fig. 1 is a plan view of the instrument with the mouthpiece end thereof broken away; Fig. 2 is a transverse section substantially along the plane indicated by the line 2-2 of Fig. 1; Fig. 3 is a longitudinal section through the keyboard portion of the instrument just inside of the outer extremity of the black keys; Fig. 4 is a longitudinal section of the keyboard portion of the instrument in the region where the valve actuation takes place; Fig. 5 is a perspective view of a key and the connections between this key and a valve member; Fig. 6 is a horizontal section through the keyboard portion of the instrument, taken below the keys; Fig. 7 is a broken longitudinal vertical section of a portion of the tone tube

of the instrument, designed to show the means for operating the register key; Fig. 8 is a longitudinal view similar to Fig. 3, but showing a modified form of construction in which the operating mechanism is divided into four groups instead of two; and Fig. 9 is a transverse section similar to Fig. 2 showing this modification.

Referring more in detail to the annexed drawings, numeral 1 designates the sound tube and 2 the bell of the instrument tube proper to which is attached a mouthpiece carrying a reed, not shown in the drawings. Attached to this tube is a body member 3 hollowed out in the interior for the reception of certain operating mechanism. Secured to one side of the sound tube are parts 4 and 5 by means of which the instrument is held in the left hand while the same is being played. Adjacent the part 4 is a projecting member 6 which is secured to a slide bar 7 by means of which the register valve 8 is controlled. The valve carrier 9 is pivoted upon a rod 10 and has mounted therein a pin 11 which is engaged by a cam surface 12 formed upon the slide rod 7, the latter being guided in its longitudinal movements by pin and slot connections 13. It will be apparent from the foregoing that when the operating member 6 is pulled or pushed toward member 4 the slide bar 7 will push pin 11 outwardly, thus raising the valve 8 from the aperture which it covers. This will change the register of the instrument approximately one and one-half octaves.

The valve 8 is often referred to as the register key and this expression will be used in this application with that meaning.

The rod 10 is mounted in a plurality of brackets 15 and 16 so that it remains rigidly in place relatively to the sound tube 1. On this rod are mounted, pivotally, a series of levers 17, 18, 19, 20 and 21, each carrying a valve 8. Each of the levers is spring pressed by a spring 22 which may be of any desired form. The form shown is merely used by way of illustration and, if this form were used, it would be necessary to secure one end thereof to the tube, as shown in Fig. 1, or provide other means for preventing that end from raising when a valve is opened. Any other suitable arrangement for operating the levers to close the valves 8 may be used. The levers 17 are shown as being straight, while 18, 19, 20 and 21 are

shown in Fig. 1 as being offset. This is in order to avoid the necessity of extending the body 3 and the keyboard the full length of the tube 1, as will be apparent from Fig. 1.

It is a well known fact that with an instrument of this character, opening of the valves nearer to the mouthpiece raises the pitch of the tone produced. Also, in the standard piano keyboard, the keys farther to the right produce the higher tones. In order, therefore, to adapt the piano keyboard to an instrument of the type referred to, it was necessary to provide means for connecting the keys at the farther end of the keyboard with the valves at the nearer end and vice versa. This was accomplished by having a series of tubular members concentrically mounted as shown in Figs. 3, 6 and 8. Referring more especially to Figs. 2 and 3, it will be seen that rods 24 and 25 are pivotally mounted in the body member 3, and upon each of these rods is mounted a tube 26 carrying successively larger tubes 27, 28, etc.

Secured adjacent opposite ends and to opposite sides of the rod 24 are arms 31 and 32 which, together with the rod 24, constitute a lever transmitting motion from a key to a valve operating lever. From this it will be seen that pressure upon key 33 which is at the end nearest the mouthpiece, will cause actuation of the valve controlling lever 21 at the farther end of the tube 1. Similarly, actuation of keys 34, 35, etc., will, through the instrumentality of arms 36, 37 and 38, 39, etc., and the intervening tubes 26, 27, etc., cause actuation of valve levers 21 and 20, 20, 19, etc. From the foregoing it will be apparent that actuation of the key 40 at the middle of the keyboard will, through the cooperation of arms 41 and 42 and tube 43 cause actuation of three valve levers 17 the highest of which is specifically designated 44 in Fig. 1. The key next to key 40 and which is designated by the numeral 45 will act through corresponding arms 46 and 47 and a sleeve on rod 25 to acuate the valve lever next higher than that one indicated by the numeral 44 together with the one marked 44 and the one next lower. Similarly arms 48, 49, 50, 51, etc., which are respectively connected in pairs to sleeves carried by rod 25 will be actuated by keys 52, 53, etc. From this it will be apparent that the key farthest to the right in Fig. 1 will actuate the valve lever next to the lever 9 carrying the register key 8 together with the two next lower. The arms 46, 47, 48, 49, 50, 51, etc., carried by the sleeves on the rod 25 have been omitted in Fig. 6 in order to avoid confusion, but their positions have been designated by dotted lines in order to make the arrangement of the parts clear. In Fig. 3

the corresponding sleeves 26, 27, 28, 29, etc., mounted on rods 24 and 25 have been designated by the same numerals.

One edge of body 3 is shown as being provided with supporting brackets 55 by means of which the tube 1 is supported in place. The opposite edge of body 3 has extending inwardly a flange 56 perforated for the reception of rods 57 and 58 which serve as connection means between the keys of the keyboard and the arms 31, 36, 38, 41, 46, 48, etc., of the levers by means of which the valve levers 17 to 21 inclusive are actuated. The opposite arms 37, 39, 42, 47, 49, 51, etc., of the levers mounted upon rods 24 and 25 have connected therewith series 59 and 60 of push rods whereby motion of the levers is transmitted to cross-heads 61, 62 and 63. By reference to Fig. 1, it will be seen that the cross-head 61 engages but a single lever, this lever being numbered 21. This is the lever which is acuated when key 33 is depressed. Depression of key 34 will rotate a sleeve 26 upon the rod 24, actuating arm 37 and its connected push rod 59. This, being connected to the first cross-head 62, will actuate levers 20 and 21, since the cross-head engages an extremity of each of these levers. Similarly, actuation of key 35 actuates the next rod 57, thus actuating parts 38, 27, 39, 59, 62, and 19. Each of the cross-heads 62 controls two of the valve levers, while each of the cross-heads 63 controls three of the valve levers, thus actuating as many valve members. One purpose in opening more than one valve at a time is in order to get purer tones than would be produced if just a single valve were opened. It is believed that from the foregoing the operation of the keys and valves will be clear without going into a detailed explanation of the operation of each one and a further statement thereof will, therefore, not be made.

It will be observed that each of the keys is designated by two different letters. The lower one of these indicates the tone which will be produced when playing the lower register, while the higher one will be produced when playing the higher register, that is, when the register valve 8 is open. Starting with key 33, depression of this and blowing through the reed in the ordinary manner will produce the tone C. Shifting from key 33 to key 34 will raise the pitch one-half tone to C sharp, while depression of key 35 will raise the pitch another half tone to D. Proceeding further, the tones follow in the manner of the ordinary keyboard until a sharp is reached at the middle of the board. Here, A sharp is represented by a white key instead of a black key as is customary, and B is represented by a black key instead of a white key. These two are the only changes in the lower register and

- the only changes in the upper register are at the extreme upper limit thereof where F is represented by a black key and F sharp by a white key. Upon examination it will be seen that the tones G, G sharp, A, A sharp and B of the lower register are repeated as the beginning tones of the upper register. It is thus possible to play a few tones in either of the registers, so that it is not necessary to shift from one to the other every time one crosses the normal division line between the two registers.
- Each of the rods 59 and 60 is surrounded by a coil spring 65 which engages at one end the bottom of a trough 66 and at its other end a collar 67 on its respective rod. Each of these rods is slideable through the bottom of the trough 66 and, as heretofore indicated, carries at its upper end one of the cross-heads 61, 62, 63. The keys are pivoted at their inner ends upon a rod 68 mounted, preferably, in the body member 3 and have their upper movement limited by a cross-bar 69 fastened at its respective ends to the said body member. It will thus be apparent that the keys can be pressed downwardly to open the valve but cannot move upwardly farther than the bar 69 will permit them to go.
- The substantial variation of the construction shown in Figs. 8 and 9 from that shown in the other figures is in the use of a larger number of rods 71, 72, 73, 74, corresponding to rods 24 and 25 of the other form. It is possible to use three or any other desired number of rods up to one for each key, but increasing the number of the rods increases the complexity and weight of the device. It is now believed preferable to use but two supporting rods for the various operating levers. Since the construction and operation of the modification will be understood from the foregoing disclosure of the preferred form, detailed explanation thereof is not given, it being merely remarked in passing that parts 71, 72, etc., 57, 58, 59 and 60, correspond to and have the same functions as like rods in the preferred construction. Also, the sleeves mounted upon the rods 71, 72, 73 and 74 are the equivalents of and perform the same functions as the corresponding sleeves in the other structure. Furthermore, there are arms secured to the sleeves which cooperate with the various push rods 57 and 60 inclusive to perform the functions 55 above described.
- Another structure which is the equivalent of the structures shown is one in which the tube 1 is mounted substantially in the position occupied by cross bar 69 and the tube 60 and keyboard are mounted directly above the body 3 instead of the tube being offset laterally as in the preferred construction. This necessitates reversing the positions of pivot bar 10 and trough 66 and the direction 65 of the valve actuating levers. Otherwise this construction is substantially the same as the constructions shown.
- Among the various features which I consider novel are the keyboard arrangement, 70 connecting the keyboard to the valve levers in such a manner that operating the keys in the customary manner will produce the corresponding rise or fall in tone, design of the instrument so that a small number of keys 75 may give a much wider range of tone, so constructing the instrument that a single key will raise a plurality of valve levers for the purpose of clarifying the tones, said levers being raised the same distance by a 80 single key and without lost motion due to connecting one valve lever to another, and so arranging the keyboard that a portion of the keys at one end of the keyboard will duplicate the tones produced by corresponding keys at the other end of the keyboard. It is, of course, understood that the specific description of the structure set forth above may be departed from without departing from the spirit of my invention as set forth 85 90 in this specification and the appended claim.
- Having now described my invention, I claim:
- In a musical instrument having a tubular body, means for producing a series of tones 95 by the opening and closing of a series of openings, and means for moving the first named means including a key board, the keys of which, at one side of the middle, control the first named means at the opposite side of the middle.
- In witness whereof, I hereunto subscribe my name to this specification.
- CHARLES F. SMITH.
